UNITED STATES PATENT OFFICE.

CHESTER H. BEACH, OF RACINE, WISCONSIN, ASSIGNOR TO WISCONSIN ELECTRIC COMPANY, A CORPORATION OF WISCONSIN.

ELECTRIC GRINDER.

1,391,039.

Specification of Letters Patent. Patented Sept. 20, 1921.

Application filed May 23, 1919. Serial No. 299,315.

To all whom it may concern:

Be it known that I, CHESTER H. BEACH, a citizen of the United States, residing at Racine, in the county of Racine and State of Wisconsin, have invented certain new and useful Improvements in Electric Grinders, of which the following is a specification.

My invention relates to improvements in universal electric grinders.

10 One object of the invention is to provide a high speed grinder comprising a motor adjustable with reference to its support, whereby said motor may be swung to different positions of adjustment to prevent interference 15 with the work piece being ground.

Another object is to provide a high speed grinder which may rotate at a very high rate of speed without substantial vibration, whereby the grinding wheel may grind with 20 extreme accuracy.

A further object is to provide means for adjusting the belt tension and maintaining the proper tension regardless of the adjustment of the motor with reference to its support. 25

In the accompanying drawings I have illustrated a practical and successful embodiment of the invention. The invention may be embodied in other forms, however.

30 In the drawings—

Figure 1 is a front elevation of the grinder;

Fig. 2 is a side elevation thereof, certain parts being broken away to disclose the construction;

Fig. 3 is a front elevation of the motor, the supporting means therefor being shown in section;

Fig. 4 is a partial end elevation and partial section taken on the line 4—4 of Fig. 1; and

Fig. 5 is an elevation of one of the grinding tools.

The motor 1 may be of any suitable type, 45 but is preferably provided with a very accurately balanced armature, whereby vibration is avoided. The armature is mounted on the usual armature shaft 2, the latter carrying a driving pulley 3 on one end thereof. A belt 4 drives a large pulley 5, the latter being mounted on the reduced end 6 of the driving spindle 7 of the grinder. Said spindle is provided with ball bearings 8, 9, the outer race-ways of which are a snug fit 50 within the housing 10 and are prevented

from turning therein by means of studs 11, which project into a groove 12 in each outer race-way. The said housing constitutes a portion of the base member 13, which latter has a dove-tailed sliding connection with the 60 supporting member 14, the latter being carried by the plate 15, to which it is secured by studs 16 passing through elongated slots in said plate, thereby providing for a certain adjustment relatively. Said plate, in 65 turn, is carried by a supporting arm 17, to which it is rotatably secured by a stud 18, said arm being arranged to be mounted in the tool post 19 of a lathe, for example, and being adjustable therein. The motor 1 is 70 received within an arc-shaped cradle 20, being secured thereto by studs 21 and cushioned by bushings 22, made preferably of rubber, whereby such slight vibration of the motor as may exist is not transmitted to the housing 10 and the grinder spindle 7. As a result of this arrangement and of the balancing of the motor armature an unusually 75 smooth running driving spindle results.

The cradle 20 is provided with an apertured lug 23, which is received between a pair of ears on a cylindrical member 25, a rod 26 passing through alined openings in said parts and constituting a pivotal support about which the motor may swing. The position of the motor with respect to said cylindrical member 25 is adjusted by means of a knurled nut 27 mounted on a screw-threaded spindle 28 and coöperating, respectively, with the motor cradle 20 and a projecting lug 29 on said cylindrical casing. By means of this knurled nut the belt tension may be adjusted and maintained. The cylindrical member 25 surrounds a sleeve 30, and is secured thereto, whereby it turns 90 therewith. Said sleeve projects at each end into the housing 10, and is rotatable therein. With this arrangement the motor may be swung through a considerable angle and locked in any position of adjustment by 95 means of a locking pin 31, which is held by a spring 32 in any one of a number of radial openings 33 in said rotatable sleeve 30. In Fig. 4 the dotted line position illustrates an adjustment of the motor of 180° from the full line position. The belt tension is maintained in any position of adjustment. The grinding wheel 34 is mounted on a suitable tapering spindle 35, which is screwed into a recess in the end of the spindle 7. With this 100 105 110

arrangement the grinding wheel may be readily removed and a different one substituted.

In Fig. 5 I have illustrated a much smaller grinding wheel 36, adapted for internal grinding, which is mounted on the longer spindle 37 whereby it may project into the recess, the wall of which is being ground, the end being tapered and screwed 10 threaded to enable it to fit into the recess in the driving spindle 7. With the arrangement described the various grinding wheels inserted in the driving spindle may be adjusted to any desired position with respect 15 to the member to be ground. An adjustment vertically and in any plane horizontally may be effected by means of the usual adjustments provided through the lathe, in the tool post of which the grinder 20 is mounted. In addition, a further adjustment is available by virtue of the dove-tail connection between the base 13 and the support 14. The piece to be ground may project in such a manner that the motor 1 25 would interfere with it and prevent such an adjustment of the grinder as a whole as would enable the grinding wheel to grind the desired surface. Such interference is avoided, however, by the provision of the 30 means described for swinging the motor to different positions with reference to its support. By virtue of the adjustments described surfaces may be accurately ground which are comparatively inaccessible.

35 I claim:—

1. A universal grinder comprising a housing, a grinder spindle rotatably mounted therein, and an electric motor mounted to swing about said housing whereby it may 40 be adjusted to different radial positions with reference thereto.

2. A universal grinder comprising a housing, a grinder spindle rotatably mounted therein, an electric motor mounted to swing 45 about said housing whereby it may be adjusted to different radial positions with reference thereto, and means for locking said motor in any position of adjustment.

3. A universal grinder comprising a housing, a grinder spindle rotatably mounted therein, an electric motor mounted to swing 50 about said housing whereby it may be adjusted to different radial positions with reference thereto, a driving belt from the motor shaft to said spindle, and means for adjusting the belt tension.

4. A universal grinder comprising a supporting member, a motor mounted to swing 55 about said member and having an armature shaft, a spindle rotatably mounted in said member, a driving belt from said armature shaft to said spindle, means pivotally supporting said motor with reference to its first-mentioned support, means for swinging 60 said motor about said pivotal support to

adjust the belt tension, and means for maintaining said motor in any position of adjustment with reference to said first support.

5. The combination with a universal 70 grinder, of a supporting member therefor, a sustaining arm secured to said supporting member, a pair of dove-tail members carried by said arm, an electric motor mounted to swing about one of said dove-tail members, 75 and a grinding spindle arranged to rotate at the axis about which said motor swings whereby said spindle may be driven from said motor in any position of adjustment of the latter without varying the distance between said driving and driven spindles, and whereby said driven spindle may be adjusted in any desired position and said motor adjusted to avoid interference with the work 80 to be ground.

6. In combination, a housing, a rotatable spindle mounted therein, a barrel within said housing, an electric motor mounted to turn with said barrel, and locking means in said housing for locking said barrel and 90 hence said motor in different positions of adjustment, said motor being also adjustably mounted with reference to said barrel.

7. A universal grinder comprising a supporting base, a grinding spindle supported 95 thereby, and a motor also supported by said base for driving said spindle and movable in a circular path with reference to said spindle as a center.

8. In combination, a support, a base carried thereby and adjustable in more than one direction, a spindle rotatably supported by said base, a motor supported by said base, means for driving said spindle from said motor, and means for adjusting said 100 motor about said spindle as a center.

9. In combination, a supporting base having two projecting parts with aligned openings therein, ball bearings in each opening, a grinding spindle mounted in said ball 110 bearings, an electric motor having a supporting bracket received between said two projecting parts and clearing said spindle, and a belt for driving said spindle from the motor shaft.

10. In combination, a supporting arm to be clamped in the tool post of a lathe or other machine tool, a base adjustably mounted thereon, a member having a sliding connection with said base and having 102 a pair of spaced cylindrical elements thereon, a cylindrical motor-supporting bracket fitting between said cylindrical elements and mounted to swing about the axis thereof, a driven shaft passing through said cylindrical elements, and a shaft on the motor for driving said first shaft.

11. An electric grinder, comprising a base, a supporting member having dovetailed engagement therewith and having aligned cy- 130

lindrical projections, a sleeve having a sliding fit within said cylindrical projections, a bracket secured to said sleeve, a motor carried by said bracket, and a spring-pressed plunger for locking said sleeve in predetermined rotative positions within said cylindrical projections. 15

12. An electric grinder, comprising a base, a supporting member having dovetailed engagement therewith and having alined cylindrical projections, a sleeve having a slid- 20

ing fit within said cylindrical projections, a bracket secured to said sleeve, a motor carried by said bracket, a spring-pressed plunger for locking said sleeve in predetermined rotative position within said cylindrical projections, and a threaded shaft for adjusting said supporting member and motor with reference to said base.

In testimony whereof, I have subscribed my name.

CHESTER H. BEACH.
